UNITED STATES PATENT OFFICE.

NICHOLAS H. MOROZOWICZ, OF BELLEVUE BOROUGH, AND JOHN R. A. FARR, OF BEN AVON BOROUGH, PENNSYLVANIA.

HEEL CONSTRUCTION.

1,282,274.

Specification of Letters Patent. Patented Oct. 22, 1918.

Application filed August 2, 1917. Serial No. 184,027.

To all whom it may concern:

Be it known that we, NICHOLAS H. MOROZOWICZ and JOHN R. A. FARR, both citizens of the United States, and residents, respectively, of the boroughs of Bellevue and Ben Avon, in the county of Allegheny and State of Pennsylvania, have invented or discovered certain new and useful Improvements in Heel Construction, of which the following is a specification.

Our invention consists in a certain new and useful improvement in rubber heels for boots and shoes, and more particularly comprises improved means for attaching to a rubber heel an outer tread or wearing surface of leather or some other wear resisting material.

The use of a rubber heel where the resilient material forms the tread surface which comes into contact with the ground is attended by the danger of slipping, especially where the heel is worn by use, and also the tendency is to aggravate fallen arch trouble.

It has been recognized that the ideal heel would be one with an outer tread surface of leather and a resilient rubber body portion interposed between the outer tread and the permanent heel base of the shoe, but great difficulty has been met in properly attaching the leather tread to the rubber in such a manner that it will not easily come off and at the same time the resiliency of the heel will not be destroyed or materially impaired.

We overcome these difficulties by providing the rubber heel with members of rigid material, such as wood, whose heads or enlarged portions are seated in recesses in the inner face of the rubber, said recesses being of sufficient depth to prevent the members coming into contact with the heel base of the shoe when the rubber is compressed, and the members are provided with shanks or projecting portions extending through holes in the rubber to the exterior surface of the same and to which the leather tread is secured by screws or nails.

In the accompanying drawings, Figure 1 is a perspective showing our improved heel structure before it is applied to the shoe; Fig. 2 is a section taken along the line II—II in Fig. 1, but showing the heel structure attached to the heel base of a shoe; Fig. 3 is a top plan view of a modified form of our heel structure; Fig. 4 is a sectional view of the same taken along the line

IV—IV in Fig. 3; Fig. 5 is an elevation of the form of attaching member shown used in Figs. 1 and 2 for securing the leather tread to the rubber heel, and Fig. 6 is a similar view of the form of attaching member shown used in Figs. 3 and 4.

The following is a detailed description of the drawings, reference being first had to Figs. 1, 2 and 5.

A represents a leather tread or lift which is to be used as the portion of the heel structure which comes in contact with the ground in walking. B is the rubber portion of the heel, and C is the leather base for the heel which is permanently attached to the body 70 of the shoe.

D represents members of wood or other rigid material whose enlarged bodies or heads are seated in recesses 1 sunk in the upper surface of the rubber heel B and 75 whose shanks extend through smaller holes 2 to the outer surface of the rubber heel B. The leather tread A is attached to the outer surface of the rubber heel B by means of screws or nails 3 which are driven through 80 the leather tread into the outer ends of said shanks of the members D. The shanks are preferably short enough to require a slight compression of the rubber to bring the tread up snug against the face of the rubber and 85 to hold the heads of the members D in the bottoms of the recesses out of all possible contact with the solid heel base C.

The recesses 1 are deep enough to prevent the heads of the members D coming 90 into contact with the heel base C when the rubber is compressed by the action of the shoe in being worn.

The heel structure, comprising the tread and rubber heel may be attached to the shoe 95 by the usual nails 4 which are driven through annular washers 5 embedded in the rubber, holes 6 being provided leading down through the tread and rubber to said washers so that the nails can be conveniently 100 driven into place.

In Figs. 3, 4 and 6, we show substituted for the members D, the bridge members D¹ comprised of two or more studs 7 and a connecting bridge or web 8. The bridge 8 occupies a relatively deep channel 9 sunk in the inner surface of the rubber heel while the studs 7 extend through holes 10 to the outer surface of the rubber heel where the leather tread is attached by the screws 3.

It is evident that the leather tread provides a flat, firm surface and is securely attached to the rubber heel so that a firm stand will be obtained by the wearer without wobbling, and at the same time the resiliency is not impaired for there can be no contact between the members D or D¹ and the heel base C. The members cannot be pulled through the rubber so that the leather tread will not be torn off as long as the screws or nails 3 remain in place. The leather tread may be removed and a new one put in place when worn out.

We prefer to make our attaching members D or D¹ of wood, but metal or other suitable rigid or semi-rigid material may be substituted, the outwardly protruding portions of said members being in such case preferably provided with threaded holes for the application of the screws 3.

Although for general use a tread of leather is found to be the most suitable, it will be understood that a tread of metal or any other suitable material may be substituted, as the particular need may dictate.

What we desire to claim is:—

1. A heel structure for a boot or shoe comprising a body of resilient material adapted to be attached to the heel base of the boot or shoe and provided with recesses sunken in its inner surface and holes extending from said recesses to the outer surface of said body, members of rigid material having enlarged portions seated in said recesses out of contact with said heel base and reduced portions which extend through said holes to the outer surface of said body and a tread member of non-resilient material abutting against the outer ends of said members and rigidly attached thereto, substantially as and for the purposes set forth.

2. A heel structure for a boot or shoe comprising a body of resilient material adapted to be attached to the heel base of the boot or shoe and provided with a plurality of holes extending through said body, the inner ends of said holes being countersunk to provide recesses, rigid members having enlarged heads seated in said recesses out of contact with said heel base and reduced shanks which extend through said holes to the outer surface of said body, and a tread member abutting against the outer ends of said shanks and rigidly attached thereto, substantially as and for the purposes set forth.

3. A heel structure for a boot or shoe comprising a body of resilient material adapted to be attached to the heel base of a boot or shoe and provided with an aperture extending entirely through the same, a rigid member arranged within said aperture and extending therethrough, and a tread member abutting against one end of the rigid member and rigidly attached thereto.

4. A heel structure for a boot or shoe comprising a body of resilient material adapted to be attached to the heel base of the boot or shoe and provided with an opening of stepped formation extending entirely through said body, a rigid member having an enlarged head portion and a reduced end portion arranged within the opening in the body and extending therethrough, and a tread member of non-resilient material abutting against the reduced end portion of said rigid member and rigidly attached thereto.

Signed at Bellevue, Pennsylvania, this 30th day of July, 1917.

NICHOLAS H. MOROZOWICZ
JOHN R. A. FARR.
